D 16225

UNITED STATES PATENT OFFICE.

FREDERICK MANKEY, OF WILLIAMSPORT, PENNSYLVANIA.

DESIGN FOR A PANEL.

SPECIFICATION forming part of Design No. 16,225, dated September 8, 1885.

Application filed July 18, 1885. Term of patent 7 years.

To all whom it may concern:

Be it known that I, FREDERICK MANKEY, of Williamsport, Lycoming county, Pennsylvania, have invented and produced a new and original Design for Panels, of which the following is a specification, reference being had to the accompanying photograph, forming part hereof.

The figure is a plan view of a panel having my new design.

My design is intended for panels such as are used for the ornamentation of ceilings, doors, wainscots, &c.

My design consists in a central portion of the panel formed of truncated rectangular pyramidal elevations A. At the corners of the panel are rectangular pyramids B, smaller than the elevations A. Along the edges of the panel are elongated pyramidal figures C. Between the various elevations are transverse channels or spaces D and longitudinal channels E, of rectangular cross section. Upon the summit of each of the elevations A, I may form an ornamental figure—such, for example, as is represented in the photograph. The number of elevations A or B, provided they are symmetrically arranged, is not material.

I claim—

1. The design for a panel, substantially as herein shown and described, consisting in a central portion composed of rectangular truncated pyramids A, rectangular pyramids B at the corners of said panel, and elongated pyramidal elevations C, arranged around the edge of said panel, with intermediate transverse channels, D, and longitudinal channels E, of rectangular cross-section.

2. The design for a panel, substantially as shown and described, consisting in a central portion composed of rectangular truncated pyramids A, each pyramid having on its summit an ornamental figure, (such as represented,) rectangular pyramids B at the corners of said panel, and elongated pyramidal elevations C, arranged around the edge of said panel, with intermediate transverse channels, D, and longitudinal channels E, of rectangular cross-section.

FREDERICK MANKEY.
